C. K. PRINCE,
COMBINED MOLD POURING AND WEIGHTING UNIT,
APPLICATION FILED AUG. 9, 1919.

1,339,133.

Patented May 4, 1920.

INVENTOR,

Clarence K. Prince,

BY

Harry W. Brown

ATTORNEY.

UNITED STATES PATENT OFFICE.

CLARENCE K. PRINCE, OF WESTFIELD, MASSACHUSETTS.

COMBINED MOLD-POURING AND WEIGHTING UNIT.

1,339,133.

Specification of Letters Patent.

Patented May 4, 1920.

Application filed August 9, 1919. Serial No. 316,467.

To all whom it may concern:

Be it known that I, CLARENCE K. PRINCE, a citizen of the United States of America, residing at Westfield, in the county of 5 Hampden and Commonwealth of Massachusetts, have invented certain new and useful Improvements in Combined Mold-Pouring and Weighting Units, of which the following is a specification.

10 This invention relates to improvements in making metal castings. An object of the invention is to provide a device for quickly and effectively weighting the flask when the same is being poured usually located on a 15 suitable platform. Heretofore it has been the common practice, in foundry operations, for the workmen to place, by hand, the usual weights on the flask. These operations are not only slow, but are expensive. The present 20 invention is designed to overcome these objections by providing an apparatus for quickly lowering a weight onto the flask that can be readily operated by only one workman.

25 The present invention forms a part of an apparatus that is shown and described in an application filed by me August 9, 1919, Serial No. 316,468, for a process of and apparatus for carrying out all of the operations or steps from the point, or place, 30 where the molds are made until the empty molding frames, the cope and nowel, are returned to the molding position. Said apparatus and process comprises in general, an 35 apparatus for molding and transferring said molds or flasks, onto a suitable platform, preferably one composed of rollers; an apparatus for weighting and pouring, an apparatus for dumping the finished castings, and 40 finally returning the empty molds to the molding positions. The present invention has to do with that part of the apparatus which relates to the weighting and pouring step when located on the platform having 45 rollers.

In general the present invention comprises a suitable support or if desired, track-way 50 having depending therefrom a plate which engages the flask, which plate forms the weight proper; links connected to this plate, and an operating lever connected to the links, which lever is pivotally supported on the fixed support or track-way whereby the workman can readily raise and lower the 55 weight onto and from the flask. This plate is provided with an opening which registers

with the sprue in the flask, whereby when the flask is poured the molten metal passes through the opening in the plate and into the mold.

60 One of the objects of the present invention is to so construct the weighting plate that one end of the same will engage the flask first and from this end the plate is gradually applied to the upper surface of 65 the flask.

With these, and other objects in view, reference is made to the drawings and accompanying description.

70 Figure 1 is an end elevational view showing a portion of the roller platform on which the bottom board and flask are placed; the flask is shown on the bottom board and the weight on the flask.

75 Fig. 2 is a side elevational view showing one of the rollers of the platform, the bottom board with the flask thereon, and the weighting plate at the moment of applying the same to the flask, one end of the plate striking the flask first; this view shows the 80 operating handle in different positions, its support and connecting links between the handle and the plate.

85 Referring to the drawings in detail, 1 designates the roller or other platform on which the usual bottom board 2 and its runners 3 are placed. This platform is of the gravity runway type as shown and described in my co-pending application above referred to, Serial No. 316,468, filed 90 August 9, 1919. The cope and nowel of the flask are indicated at 4 and 5, respectively. 6 designates the weight proper which engages the top or upper edge of the cope 4. This weight is formed with a pouring opening 7 which registers with the sprue 8 in the flask. Connected to the ends of the weight 6 are links 9 and 10 by means of the pins 11 and 12; these links are joined together at their upper ends by means of the 95 common rod or pin 13 and this pin is connected to the link 14 which in turn is connected to the operating lever 15 by means of the pin 16 which is pivotally supported on the supporting structure 17 at 18. The 100 operating lever or handle 15 as shown, extends downward within easy reach of the operator. Any suitable device as a hook 19 is provided for holding the plate 6 elevated.

110 It should be stated and noticed that the links 9 and 10 are of equal length, and

forming with the plate 6 an equilateral triangle, whereby when the weighting plate is lowered the end 6', to which the links 9 are connected, will strike the upper edge of 5 the cope first on account of the inclined position of the bottom board and then as the operating lever 15 is raised it allows the weight to gradually settle onto the flask, the pressure will thus be gradually 10 applied to the flask thus forcing out any confined air that may be retained between the plate and the flask. This construction constitutes a pendant device which permits the weighting plate to readily assume an 15 inclined position. The lowered position of the plate is indicated by the dotted lines 6² in Fig. 2. After the flask is poured the weight is lifted and the flask moved along the platform to that part of the apparatus 20 where the flasks are emptied. A new flask is then moved into position under the weighting and pouring apparatus and the same operations repeated.

It is to be understood that the present invention is not in any way limited to the use 25 of a single weighting and pouring apparatus as shown, but a plurality may, if desired, be placed end to end forming a series along and over the platform 1 whereby several flasks may be simultaneously weighted 30 and poured. It is to be understood that the apparatus is not limited to use with an inclined bottom board as it is equally applicable for use when the bottom board is in a 35 horizontal position.

What I claim is:

1. In a combined apparatus for weighting and pouring flasks, the combination, of a weighting plate to engage the flask, links 40 connected thereto, and operating device for the links, a bottom board for the flask and means for supporting the bottom board and flask on a gravity runway.
2. A weight and pouring device for flasks 45 comprising, in combination, a weight proper, means for supporting the same in a pendant manner to permit one end of the weight to engage the flask before the other should the flask be arranged in an inclined 50 position and means for movably supporting

the flasks on a gravity runway during the weighting and pouring operations.

3. A weight and pouring device comprising, in combination, a plate forming the weight proper inclined, links connected thereto, a supporting structure, an operating lever pivotally connected to said structure and to said links whereby the plate may be raised and lowered as described.

4. In a weighting device, the combination, of a plate having a pouring opening therethrough, a supporting structure, connecting means between the structure and the plate, said means being designed to permit the plate to assume an inclined position.

5. In a combined weight and pouring device for flasks, the combination, of a weighting plate, supporting links therefor connected thereto to permit the plate to engage 70 the flasks at one of its edges first and then gradually engage the whole of its upper surface as the plate is lowered, an operating lever connected to the links, and means for supporting said lever.

6. A weighting and pouring device for molders' flasks comprising a weighting plate to engage the cope, links pivotally connected to the plate at their lower ends, their upper ends being united by means of a common 80 pin, or the like, to form substantially an equilateral triangle which includes the links and the portion of the plate between the lower ends of the links, a single link connected to the common pin and an operating 85 lever for raising and lowering the plate connected to the other end of the last named link, whereby the links and plate will have a free or pendant action, said plate having an opening for pouring the metal into the 90 molds, as described.

7. In a combined apparatus for weighting and pouring flasks in foundry operations, the combination, of a weighting plate to engage the flasks, means connected to the 95 plate for movably supporting the plate, a bottom board, said board being movably supported on a gravity runway.

CLARENCE K. PRINCE.
